DOWNDRAFT STOVE

Lee Lockwood, Des Moines, Iowa

Application August 29, 1942, Serial No. 456,619

1 Claim. (Cl. 126—76)

1

In the art of furnaces, especially household heating coal-burning furnaces, it is highly desirable that provision be made for refueling only at long intervals, twelve or twenty-four hours, and also that provision be made for controlling the combustion from its maximum to an amount only sufficient to maintain combustion somewhat in the nature of a pilot light, without any such attention by an operator as is ordinarily required in using a poker to break up masses of caked coal in the coal magazine, and thereby feed it by gravity to the burning fuel on the grate.

The object of my invention is to provide a furnace of the magazine down draft type which is relatively light in weight and inexpensive in construction.

A further object of my invention is to provide a heater of the type employing a magazine to receive a charge of fuel of such an amount that it needs to be charged only once or twice a day, of such construction that a predetermined temperature level may be maintained for a number of hours, say six or eight, without changing damper adjustments.

More specifically, it is my object to provide a furnace in which the thin sheet metal walls of the combustion chamber at the area where the maximum combustion occurs, is prevented from burning out or being destroyed by heat by the utilization of the incoming air which is necessary for combustion purposes, in forming a constantly flowing stream of cool air directly over the outer surface of the sheet metal forming the combustion chamber, to thereby perform the double function of maintaining the sheet metal at such temperature as to prevent the heat against the inner surface from burning out the sheet metal, and at the same time pre-heating the air just prior to its entrance into the combustion chamber to aid combustion, and whereby a substantial reduction in the weight of the furnace is effected by the elimination of the necessity for such linings.

Another object of my invention is to provide a furnace of standard construction which may be manufactured by so-called quantity production and which will operate successfully with all of the various classes or kinds of coal ordinarily used for furnaces and which may be fueled with a large enough amount of coal to burn for a long period of time, for instance twenty-four hours, and which will automatically prevent the coal from caking or sticking to the sides of the fuel magazine so that it feeds by gravity to the combustion area until the magazine is completely

2

emptied, without any attention on the part of an operator.

There are certain kinds of coal now being used in furnaces which are characterized as being relatively soft and, when heated to a certain degree, will melt and become plastic and will expand and generate a gas which condenses in the form of creosote, and when this kind of coal is used in an ordinary magazine furnace, such expansion causes the mass of coal in the magazine to stick to the sides of the magazine and fail to feed by gravity to the combustion area, hence, at frequent intervals of time it must be loosened by an operator. Furthermore, some of the gas generated within the magazine condenses in the form of creosote upon the fuel door at the top of the magazine, and unless the creosote is frequently removed by an operator, it prevents the door from being tightly closed and permits the gas to escape into the household.

Another object of my invention is to provide a furnace in which any gases that may be accumulated in the upper portion of the fuel magazine are drawn downwardly into the combustion area and consumed, thereby serving a useful heating function and at the same time preventing the creation of creosote and thereby avoiding the injurious results produced by creosote in the upper portion of the fuel magazine and on the fuel door.

A further object is to provide a furnace of this class in which air for combustion purposes is fed to the combustion area and the lower part of the fuel magazine in a downwardly moving path around the entire inner surface of the fuel magazine and the entire outer surface of the column of coal, whereby combustion takes place more rapidly and completely at this point, thereby forming a cylindrical column of coked coal and ashes around the unburned column of coal, thereby preventing the coal from sticking to the fuel magazine and permitting it to freely move by gravity to the combustion area, and this regardless of whether the area under combustion at any given time is at its maximum or its minimum.

A further object is to provide means for maintaining the upper portion of the fuel magazine in a relatively cool condition to thereby prevent the generation of an excessive amount of gas within the fuel magazine without impairing the heat radiating capacity of the furnace casing.

In the accompanying drawings—

Figure 1 shows a vertical central sectional view of my improved furnace showing the same loaded

with a charge of fuel and the circulation of air and combustion gases therein;

Figure 2 shows a horizontal sectional view on the line 2—2 of Figure 1;

Figure 3 shows a horizontal sectional view on the line 3—3 of Figure 1;

Figure 4 is a vertical sectional view of the upper end of my improved stove showing the top of coal in the magazine and feed door open and the manner that the gas and air are circulated to outlet stack;

Figure 5 shows an enlarged detail vertical sectional view through the air-conducting chambers and combustion chamber taken at the side of the air supply pipe; and

Figure 6 shows a similar view taken at the opposite side of the furnace.

The furnace casing is indicated generally by the reference numeral 10; at its bottom is the usual ash pit 11 and door 12. At the top is the usual furnace dome 13, having a flue 14 extended from one side of the dome and a fuel door 15 at the side of the dome opposite the flue. There is also the usual grate 16. Between the body of the furnace and the dome is a horizontal furnace head 17 having a centrally arranged fuel opening 17a surrounded by an upright circular flange 18. A lid 19 is provided for this opening, and on the under-side of the lid is a circular channel bar 19a having a circular opening to receive the flange. An asbestos rope 20 within the channel bar engages the top of the flange 18 and forms a substantially gastight joint when the lid is closed.

Within the upper portion of the casing is the cylindrical fuel magazine 21 having a fuel capacity large enough to supply fuel for any desired period of time, for instance, twelve or twenty-four hours. Its lower end rests upon a horizontal circular plate 22 which is fixed in position within the casing by brackets 23. This plate stands spaced apart from the furnace casing all around except at the air intake port 27 where it extends to the furnace casing at 25.

A heat insulating wall 26 surrounds the fuel magazine and extends from the plate 22 to the furnace head 17 and is spaced apart from the fuel magazine and from the furnace casing. The air inlet pipe 27 enters the space between the fuel magazine and the insulated wall at its lower portion, and extends to the exterior of the furnace casing. It is provided with an adjustable damper 28 having spring blades 29 to engage the interior of the pipe and support the damper in any position and whereby the amount of air admitted may be regulated by an operator. The upper end of the fuel magazine is spaced below the furnace head at 30 to permit air within the insulating chamber to enter the top of the fuel magazine all around its circumference. This wall 26 performs the double function of providing a thin stream of air moving in an upward direction against the interior of the fuel chamber to supply oxygen for combustion around the outer circumference of the lower portion of the fuel magazine, and the wall also acts as heat insulator for the fuel magazine.

Secured to the under surface of the plate 22 is an annular air-conducting chamber 31, closed at its top, bottom and outer side and having a narrow circular opening 31a at the top of its inner wall leading into the combustion chamber. At one side of the furnace is an air inlet pipe 35 leading to the chamber 31 and having a control damper 36. The said inner wall is of larger di-

ameter than the interior of the fuel chamber directly above it.

Below the air-conducting chamber 31 is a similar air-conducting chamber 37 having an air inlet pipe 38 and a damper 39, and a narrow circular air passageway 39a at the top of its inner wall leading to the combustion chamber. This air chamber 37 is of smaller diameter at its interior than that of the chamber 31.

In the bottom wall of the chamber 37 is a series of air passageway openings 38a arranged near the inner wall and leading to the lower part of the combustion chamber at points which are spaced above the fuel upon the grate, whereby the flow of air is not retarded by contact with the fuel.

I employ relatively thin sheet metal especially for the parts forming the fuel and combustion chambers for purposes hereinafter made clear.

In practice, and assuming that a normal fire is burning in the furnace, the air necessary for combustion purposes is admitted at three points. That which enters through the inlet pipe 38 is drawn rapidly by the draft to flow through the air-conducting chamber 37 and from the top of the chamber into the combustion chamber, and also through the openings in the bottom of the chamber into the combustion chamber below the chamber 37. This provides two important results, the air necessary for combustion purposes at the bottom part of the furnace is pre-heated because it is directed across the outer surface of the inner wall and upwardly and also across the bottom of the chamber, and further serves to cool the inner wall and bottom wall to such extent as to prevent the thin sheet metal from burning out. In practice I have demonstrated that when the furnace is burning at maximum, the increased draft draws enough cool air through the passageway and across the surfaces exposed to the heat to prevent burning out.

The air that is admitted through the pipe 35 travels in a similar manner but it is not necessary to have the openings in the bottom wall of the chamber 31 because the current of air which flows over the inner wall of the chamber 37 cools the bottom wall 32 of the chamber 31 at the point most exposed to the heat. The air that passes through the pipe 27 cools the bottom wall 22 and the outer surface of the combustion chamber and is pre-heated when entering the combustion chamber. In this manner every part of the thin sheet metal combustion chamber is kept sufficiently cool to prevent burning out, and this important and essential result is accomplished by utilizing only the amount of cool air necessary for combustion purposes, which amount and speed of travel of cool air is automatically increased during maximum combustion to thereby prevent destruction of the sheet metal.

In practical use and assuming that the fuel magazine is filled with soft coal of the kind which expands when heated and forms a gas which condenses into creosote, and assuming further that the coal on the grate is burning—

If it is desired to have a relatively low fire, then the lower damper 39 is opened, the damper 36 closed and the damper 28 opened to a slight degree. Air for combustion purposes will enter the lower air supply chamber and from it flow into the combustion chamber around its entire circumference, this will ignite the gases and will flow downwardly around the column of fuel or ashes, and upwardly between the furnace casing and fuel magazine to the furnace dome, and up through the flue. If a greater degree of heating

is desired, then the damper 36 is also opened. When this has been done the combustion area extends up into the column of coal a substantial distance and a quantity of coal not previously in the combustion area is ignited and burned, in a manner somewhat similar to the placing of a fresh quantity of fuel upon an ordinary fire. This flow of the heated products of combustion into the furnace dome will heat the lid 19 for purposes hereinafter made clear.

Due to the tendency of the heated gases within the combustion area to rise within the fuel magazine, there will be some gas at the top of the fuel magazine which will tend to condense and form creosote. This, however, is prevented in two ways, first, the current of air admitted by the upper damper 28 will enter the top of the fuel magazine all around its circumference and carry the gases down to the combustion area all around the column of coal, and these gases will ignite and thereby increase the heating capacity. Furthermore, the lid 19 being heated prevents the gases from condensing upon the lid, hence, it is not necessary to remove creosote therefrom to keep the lid sealed in substantially gas-tight condition.

Due to the fact that gases are burning substantially all around the exterior of the column of coal and up into the fuel magazine, an outer layer of the column of coal is consumed and turned into ashes so that the expansion of the column of coal will not cause it to stick to the walls of the fuel magazine. In practice I have obtained coal having a maximum of such expansion tendency and a maximum of creosote forming quality, and I have successfully repeatedly burned an entire fuel magazine full without breaking the fuel loose from the fuel magazine with a poker, or otherwise, and without forming any perceptible amount of creosote on the furnace lid.

The furnace will work at maximum efficiency when hard coal is used, hence, it is adapted for use in every locality regardless of the kind of coal used for fuel.

By arranging the fuel door for the furnace dome at one side thereof and the flue 14 at the diametrically opposite side, then when the fuel door is opened and the lid to the fuel magazine is also open, any gases that may arise from the fuel magazine will be carried by the air currents entering through the fuel door opening to the dome into the flue and will not enter the room where the furnace is located.

I claim as my invention:

In a fuel burning heater of downdraft type having a housing, a grate extended across said housing adjacent the lower end thereof, an upright vertically elongated casing carried in a spaced relation within said housing having its lower end open and above said grate, with the upper portion of said casing defining a fuel magazine and the lower portion thereof a combustion chamber, partition means having side walls supported in a spaced relation between said casing and said housing such that the space between said partition means and said hous-

ing is open to the space above said grate to constitute a passage for flue gases, and the space between the side walls of said partition means and said casing defines an annular air chamber whereby said air chamber is in a heat exchange relation with the casing and said partition means to provide for a heating of the air therein, a top wall for said partition means positioned horizontally above said casing and formed with a fuel inlet which is open to the upper end of said casing, a cover for said fuel inlet, with said cover and top wall of the partition means constituting a closure for the upper end of said air chamber, said partition means having the lower end thereof terminating substantially at the lower end of said casing, a perforated bottom wall connected between the lower ends of said casing and said partition means, with said casing having its upper end open to said air chamber and being formed with peripheral air openings therein at a first position adjacent its lower end and at a second position spaced from said lower end whereby a first portion of air from said air chamber is admitted into said casing through the upper end thereof, a second portion of air through said air openings, and a third portion of air through the perforations in said bottom wall into the space above said grate, an air inlet means for said air chamber, and means for directing the air flowing through said air inlet means into said air chamber such that said first portion of air enters the air chamber at a position spaced below the upper end of said casing and above the air openings in said second position prior to the admission thereof into the upper end of said casing, with said first and second portions of air, on admission thereof into said casing, being moved downwardly through the casing into the space above said grate and then into said flue passage with said third portion of air, by the draft in said heater.

LEE LOCKWOOD.
